UNITED STATES PATENT OFFICE.

JOHN F. O'CONNOR, OF CHICAGO, ILLINOIS, ASSIGNOR TO WILLIAM H. MINER, OF CHAZY, NEW YORK.

ROLLER SIDE BEARING.

1,273,400.

Specification of Letters Patent. Patented July 23, 1918.

Application filed June 9, 1917. Serial No. 173,848.

To all whom it may concern:

Be it known that I, JOHN F. O'CONNOR, a citizen of the United States, residing at Chicago, in the county of Cook and State 5 of Illinois, have invented a certain new and useful Improvement in Roller Side Bearings, of which the following is a full, clear, concise, and exact description, reference being had to the accompanying drawings, 10 forming a part of this specification.

This invention relates to improvements in roller side bearings.

The object of the invention is to provide a simple and relatively inexpensive roller 15 side bearing wherein are employed gravity-controlled members separate from the roller for returning the roller to normal position after each actuation.

In the drawing forming a part of this 20 specification, Figure 1 is a longitudinal vertical sectional view of a roller side bearing showing one embodiment of the invention. Fig. 2 is a transverse vertical sectional view, taken on the line 2-2 of Fig. 1. And Fig. 25 3 is a view similar to Fig. 1, but illustrating another embodiment of the invention.

In said drawing, 10 denotes a portion of a truck bolster to which the improved roller side bearing A is preferably attached, and 25 11 the under side of a body bolster.

The roller side bearing A, as shown, comprises a base casting having a lower wall 12 riveted or otherwise secured to the bolster 10, upstanding side walls 13-13, upwardly 30 and outwardly inclined end walls 14-14, an insert tread-plate 15, and oppositely arranged, duplicate sets of inclined guiding-ledge or run-ways 16 and 17 on the inner face of each side wall 13. The anti-friction 35 roller 18 normally occupies the position shown in Fig. 1 and to maintain the latter in central or normal position, the following gravity-controlled means are employed. On each side of the roller 18 is a transversely 40 extending rod or roller 19 which extends from side to side of the casting and is supported and guided by the run-ways 16 and 17. Due to the opposite inclination of the run-ways 16 and 17, it is apparent that each 45 rod or roller 19 will normally occupy the lowermost position thereon, as indicated in Fig. 1 by the full lines. The rollers or rods 19 are each journaled at their ends in connecting links 20-20 at each end of the 50 roller, said links 20 being upwardly in-

clined, as clearly illustrated in the drawing, to thereby clear the high portions of the run-ways 16 and 17. By connecting the rollers 19 together, it is apparent that the same will move in unison and thereby employ the weight of both of said rollers to return the anti-friction roller 18 to normal position after each actuation of the latter. In Fig. 1, the dotted lines indicate the extreme position of the parts when the anti-friction roller 18 has been moved to one side and during this movement, it is apparent that the roller 18 will force the left hand rod 19 up the incline 16 and drag the other roller 19 up the corresponding parallel run-way 16. The roller 18 is limited in its movements by stop shoulders 21-21 and similarly the rods 19 are limited in their upward movements by curved recesses 22-22 on the inner faces of the end walls 14 of the base 55 casting. After the anti-friction roller 18 has been moved to the position indicated by dotted lines in Fig. 1, and the pressure from the body bolster removed, it is obvious that both the rollers or rods 19 will gravitate 60 down the run-ways 16 and thereby pull the roller 18 back to central position.

The roller 18 is centrally recessed, as indicated at 122 and a loose rod 23 may be extended therethrough, which rod is adapted 65 to freely slide back and forth in longitudinal slots 24 in the side walls 13, the rod 23 being adapted to prevent accidental displacement or removal of the roller 18.

In the construction illustrated in Fig. 3, 70 the arrangement of base casting, anti-friction roller, side walls of the base casting, end walls of the base casting, and guide-ledges or run-ways, is the same as in the structure illustrated in Figs. 1 and 2. In 75 the arrangement shown in Fig. 3, however, the gravity rods or rollers 119 are independent of each other so that, as the anti-friction roller 118 moves to either side of normal, only one of the gravity rollers 119 80 will be forced up a run-way and consequently, there will be only one of said gravity rods or rollers to force the anti-friction roller 118 back to normal position.

I claim:

1. In a roller side bearing, the combination with a base member having a bearing surface for an anti-friction roller, of an anti-friction roller, inclined guide-ways, and a gravity rod freely mounted on said 85 110

guide-ways and adapted to tangentially engage said roller, the rod normally resting in its lowermost position on the guide-ways and adapted to be displaceable upwardly 5 thereon when the anti-friction roller is moved from normal position, whereby said gravity rod is adapted to return the anti-friction roller to normal position.

2. In a roller side bearing, the combination 10 with an anti-friction roller, of a housing within which said roller is mounted and freely movable, said housing having sets of inclined guide-ways on both sides of the roller, and gravity rollers on each side 15 of the anti-friction roller riding on said inclined guide-ways and adapted to return the anti-friction roller to normal after each actuation, under the influence of gravity.

3. In a roller side bearing, the combination 20 with a base casting having parallel side walls and end walls, of an anti-friction roller mounted within said base casting,

two sets of inclined guide-ways on the inner side of each of said side walls, and transversely extending gravity rods supported 25 at their ends on said guide-ways, said gravity rods being disposed on opposite sides of the anti-friction roller.

4. In a roller side bearing, the combination 30 with a base casting having parallel side walls and end walls, of an anti-friction roller mounted within said base casting, two sets of oppositely inclined guide-ways on the inner side of each of said side walls, and transversely extending gravity 35 rods supported at their ends on said guide-ways, said gravity rods being disposed on opposite sides of the anti-friction roller, and means for moving said gravity rods in unison. 40

In witness that I claim the foregoing I have hereunto subscribed by name this 20th day of May, 1917.

JOHN F. O'CONNOR.
